SUSPENSION THEREFOR

Carl A. Eversman, Toledo, Ohio, assignor to Sheller-Globe Corporation, Toledo, Ohio, a corporation of Ohio

Filed Feb. 2, 1967, Ser. No. 613,493
10 Claims. (Cl. 312—254)

ABSTRACT OF THE DISCLOSURE

A pedestal type desk comprising basic standard pedestal weldments, and basic standard drawer weldments, and a plurality of alternative trim members and leg members readily attachable without tools whereby to produce desks of several different styles from said basic weldment; and a plurality of alternative drawer suspension elements readily attachable to the pedestals and drawers to provide several different drawer suspension modes, one of said modes permitting a drawer to be fully withdrawn from the pedestal; and a false front and finish front construction of drawers whereby the finish front may be applied by sliding onto the false front vertically or horizontally in either direction so that if a finish front must be reversed when changing a drawer from one pedestal to the other, the finish front can be reversed without special tools; whereby complete interchangeability of drawers is provided for.

Cross reference to related applications

There are no related applications presently pending.

Background of the invention

Field of the invention.—The invention pertains to the art of metal desk construction and mounting of drawers in pedestal type desks.

Description of the prior art.—Metal desks for office and the like use have heretofore been made in a variety of designs. For each design a special pedestal weldment was required and the design of the desk could not be changed without a complete rebuilding of the desk.

A great many drawer suspensions have been designed and built, these drawer suspensions have various degrees of complexity and various costs. Heretofore it has not been possible to modify the suspension of the drawers wherein at least three different suspensions may be applied to a standard drawer weldment without requiring the use of special tools.

Heretofore all suspensions for drawers and pedestal type desks have been such that the drawer could not be fully withdrawn from the pedestal so that its rear wall was at least flush with the front of the pedestal. One of the suspension modes hereafter described permits the drawer to be fully withdrawn.

Summary

The invention provides a standard pedestal weldment and a plurality of trim elements and leg elements of different designs. The trim elements and leg elements are secured to the pedestals by a stud and keyhole slot arrangement whereby a pedestal may be provided with legs at its four corners, said legs having one of several designs, and whereby legs may be provided at the outside corners only or the inside corners only of the pedestal and the remaining corners may be provided with matching trim strips, whereby several different styles of desks may be made up from a standard basic pedestal weldment simply by the application of various trim elements and leg elements.

A standard drawer weldment is provided and the pedestals are provided with standard case elements for the drawers. By simple modifications not requiring the use of spe-

2

cial tools, the drawers and the case elements may be modified to provide several different modes of suspension over a range of costs and a corresponding range of qualities.

One suspension mode made possible by the invention enables a drawer to be completely withdrawn from the pedestal so that its rear wall is at least flush with the front of the pedestal.

The standard drawer weldment is provided with a false front to which a finish front is applied by sliding on vertically either from above or from below or horizontally from the right side or from the left side, whereby a drawer having no pull on its finish front but having a lateral overhang in the kneehole space of the desk for use as a pull, is to be changed from one pedestal to another, the finish front may be removed and rotated 180° and replaced.

By a combination of the foregoing features, complete interchangeability of drawers within the pedestals of a desk and between pedestals of a desk and from one desk to another is achieved.

Brief description of the drawings

FIG. 1 is a perspective view of a standard pedestal weldment.

FIG. 2 is a perspective view of a typical leg member.

FIG. 3 is a front elevational view of the pedestal weldment of FIG. 1 on an enlarged scale.

FIG. 4 is a cross sectional view taken on the line 4—4 of FIG. 2 on an enlarged scale.

FIG. 5 is a cross sectional view of a trim strip taken in a position corresponding to the line 4—4 of FIG. 2.

FIG. 6 is a cross sectional view similar to FIG. 5 of another form of trim element.

FIG. 7 is a cross sectional view similar to FIGS. 5 and 6 showing yet another type of trim element.

FIG. 8 is a cross sectional view of the pedestal weldment taken on the line 8—8 of FIG. 3.

FIG. 9 is a fragmentary perspective view of the upper portion of the pedestal showing a top finish strip.

FIG. 10 is a fragmentary cross sectional view on an enlarged scale taken on the line 10—10 of FIG. 9.

FIG. 11 is a side elevational view with parts broken away of a standard drawer weldment.

FIG. 12 is a rear elevational view of the same.

FIG. 13 is a fragmentary side elevational view of the rear end of a drawer with an outrigger element attached for use in one mode of suspension.

FIG. 14 is a fragmentary side elevational view showing a first mode suspension using the outrigger element of FIG. 13.

FIG. 15 is an enlarged fragmentary cross sectional view taken on the line 15—15 of FIG. 15.

FIG. 16 is a fragmentary side elevational view of a standard drawer weldment with runners attached thereto for use in a second mode suspension.

FIG. 17 is a fragmentary side elevational view of the drawer of FIG. 16 showing the cooperation thereof with the case elements in the second suspension mode.

FIG. 18 is a fragmentary cross sectional view on an enlarged scale taken on the line 18—18 of FIG. 17.

FIG. 19 is a side elevational view of a cradle element for use in a third suspension mode.

FIG. 20 is a fragmentary front elevational view with parts in cross section showing the cooperation between the cradle and a drawer seated therein.

FIG. 21 is a fragmentary plan view of the cradle element.

FIG. 22 is a side elevational view with parts in section and parts broken away showing the cooperation between the drawer, cradle and the case element in the third suspension mode.

FIG. 23 is an enlarged fragmentary cross sectional view taken on the line 23—23 of FIG. 22.

FIG. 24 is a fragmentary side elevational view of a box drawer with parts in section showing how a finish front is secured to the false front.

FIG. 25 is a fragmentary top plan view of the front end of a drawer showing another mode of applying a finish front to the false front where the false front is provided with a lateral overhang type of a pull.

FIG. 26 is a fragmentary side elevational view of a file drawer with parts in section showing the attachment of a finish front.

FIG. 27 is a fragmentary top plan view of the structure of FIG. 26.

FIG. 28 is a fragmentary cross sectional view on an enlarged scale taken on the line 28-28 of FIG. 26.

FIG. 29 is a fragmentary cross sectional view on an enlarged scale taken on the line 29-29 of FIG. 24.

Description of the preferred embodiments

In FIG. 1 there is shown a standard pedestal weldment having side walls 10 and 11 and bottom wall 12. At the top of the pedestal weldment are the cross pieces 13 and 14 which are provided with members 15 for the attachment of the desk top to the pedestals. The attachment of the desk top to the pedestals does not constitute a part of this invention and will therefore not be described in detail.

The walls 10 and 11 are provided with the inwardly directed flanges 10a and 11a and the forwardly extending flanges 10b and 11b. Similar flanges are provided at the rear. The case elements 16 are secured by spot welding or in other suitable manner between the front and rear flanges 10b and 11b, respectively. The cross member 13 is provided with the downwardly turned flange 13a and the forwardly extending flange 13b, and similarly the bottom element 12 is provided with down-turned flange 12a and the forwardly extending flange 12b.

The flanges 10a and 11a at the front and rear of the pedestal weldment are provided with the keyhole slots 17 and it is by means of these keyhole slots that alternately leg members or trim members are attached to the pedestal weldment.

A typical leg member is indicated at 18 in FIG. 2 and it is provided with the headed studs 19. A leg member is attached to the pedestal weldment by inserting the headed studs 19 to the enlarged portions of the keyhole slots 17 and then sliding the leg member upwardly or pushing the pedestal downwardly with respect to the leg member. It will be understood that the dimensions of the leg member 18 are such that the two exposed surfaces of the leg member will be flush with the side wall 10 or 11. In this way leg members may be provided at each of the four corners of the pedestal.

In some cases it may be desirable that the pedestal have only outboard leg members or only inboard leg members. In such case, a trim member is applied instead of a leg member. A trim member which would be used with the leg member 18 is shown in FIG. 7. It will be observed that the trim member, which is indicated at 20, is of much lighter gauge material than the leg member since it need not carry the weight of the desk. It is again provided with the headed stud 19 and attached to the pedestal weldment in the same way as a leg member. Thus, by way of example, leg members 18 may be attached to the flanges 11a at the front and rear and trim members 20 may be attached to the flanges 10a, front and rear, in which case the pedestal will have only outboard legs. Conversely, the leg members may be attached to the flanges 10a front and rear, and the trim members attached to the flanges 11a front and rear, in which case the pedestal will have only inboard legs. (In this description it has been assumed that the pedestal of FIG. 1 and FIG. 3 is the left pedestal.)

It is, of course, also possible to omit the leg elements 18 entirely and use the trim elements 20 at all four corners of the pedestal and to use one or more central leg members attached to the underside of the pedestal weldment in any conventional manner.

FIGS. 5 and 6 show trim elements 20a and 20b, each having the same headed studs 19 for attachment but having a different cross sectional configuration. The trim element of FIG. 5 gives a beveled appearance and that of FIG. 6 gives a quarter round appearance. It will be understood that corresponding leg members are provided of a heavier gauge material such as shown in FIG. 4 but having the configurations of FIGS. 5 and 6 respectively.

From the foregoing description, it will be seen that basically any one of three types of leg and trim may be provided and that with any particular type of trim the number and location of the legs used may be varied. All of this is accomplished with a standard pedestal weldment and the changes are made without the use of special tools. Thus, if it is desired to change the style of the desk, this can be done by simply purchasing the required number of leg members and trim members of a different style.

In FIGS. 9 and 10, a top filler or trim strip is shown and is indicated at 21. This is simply attached to the flange 13b by means of sheet metal screws 22. A bottom filler or trim strip identical to the top strip 21 is attached to the flange 12b of the bottom member.

In FIG. 8 the case elements heretofore referred to are shown at 16. As best seen in FIG. 1, each case element has an upper flange 16a and a lower flange 16b. Each flange is provided with a slot 22 formed by punching out a lip 23 at its front end and each case element is provided with a stud 24 upon which a roller may be mounted as hereinafter described. As will be described in more detail hereinafter, a nylon glide may be snapped into the opening 22 and supported on the lip 23 and the flange 16b for use with a first suspension mode, there being no roller on the stud 24. In a second and third suspension mode, the nylon glide is not used and a roller is mounted on the stud 24.

A basic drawer weldment is shown in FIGS. 11 and 12. The drawer weldment is generally conventional in structure and is provided with a false front 25. At the top and bottom and on each side forwardly sloping flanges are provided. The top and bottom flanges are indicated at 26 and 27 and the lateral flanges at 28 and 29. A pair of retainers 30 are spot welded to the rear wall 31 of the drawer and these are provided with fingers 30a, the purpose of which will be described hereinafter. The basic drawer weldment shown in FIGS. 11 and 12 is used regardless of the suspension mode which is adopted. For a first suspension mode an outrigger 32 is applied to the drawer as shown in FIG. 13. The outrigger is provided with the bottom flange 32a and the lateral flange 32b for location with respect to the drawer and the outrigger is held in place by the single screw 33. The outrigger carries a roller 34.

When the drawer is equipped with an outrigger 32 at the rear thereon on each side, and a nylon glide 35 (FIG. 15) is snapped into place in the aperture 22 and resting on the lip 23, a first suspension mode is provided. In FIG. 15 the drawer side is indicated at 36 and the drawer bottom at 37. By a study of FIGS. 14 and 15, it will be apparent that the seat portion 35a of the nylon glide 35 supports the bottom of the drawer so that the drawer may slide thereon and that the roller 34 rides on the underside of the flange 16a of the case member 16. The suspension mode thus far described is a very inexpensive yet adequate suspension for an inexpensive desk, particularly where the contents of the drawer will not be heavy.

A second suspension mode is illustrated in FIGS. 16, 17 and 18. It will be observed that the drawer of FIG. 16 has a roller 34a corresponding to the roller 34 which was mounted on the outrigger 32, but here the roller 34 is mounted on a runner 38. The outrigger is removed and the runner 38 applied instead. The runner is generally Z-shaped in cross section as best seen in FIG. 18 and is provided with a tongue 38a at its front end which engages 75 in a slot in the false front and the runner is held in place

by the single screw 39. The drawer has thus been modified by substituting the runner 38 carrying the rollers 34a for the outriggers 32 carrying the roller 34. Additionally, the nylon glides 35 are not used and instead a roller 40 is mounted on the stud 24. In the representation of FIG. 18, the roller 40 is a roller bearing type of roller slipped over the stud 24 and held in place by a pressed headed nylon stud 41. Thus, in the second suspension mode the drawer is supported at the front of the pedestal by the flange 38b of the runner riding on the roller 40 and at its rear held by the roller 34a riding on the underside of the flange 16a of the case element. The operation of this suspension will be clear from a comparison of FIGS. 17 and 18. In this suspension mode, the entire suspension operates on rollers, whereas in the first mode described it rode on one roller and one nylon glide on each side.

In a third suspension mode, the case element portion of the suspension is the same as in the second mode, i.e., the nylon glide is not used and a roller 40 is mounted on the stud 24. The drawer in the third mode uses neither the outrigger nor the runner. Instead use is made of a cradle as shown in FIGS. 19 and 21. The cradle is indicated generally at 42. The cradle is basically a rectangular framework having side elements 43 and 44 which correspond to the runners 38 described above. They are substantially Z-shaped and they carry rollers 34b which correspond to the rollers 34 and 34a. The cradle 42 cooperates with the case elements heretofore described in exactly the same mode, so that as seen in FIGS. 20 and 22 the upper flanges 43a and 44a ride on the respective rollers 24, and the rollers 34b ride against the upper flange 16a. Thus, the cradle member 42 acts like a drawer of a suspension of the second mode.

The drawer itself, indicated at D in FIG. 20, simply seats in the cradle and is guided between the nylon glides 45. The drawer D is shorter than the cradle 43 so that when the drawer is pulled out, the drawer and cradle roll as a unit by means of the rollers 24 and 34b until the cradle is stopped by means of its bumper 47, whereupon further movement of the drawer is a sliding movement on the glides 45. In this way, the rear of the drawer may be pulled out to a position at least flush with the front face of the pedestal. When the drawer is pushed in, generally the drawer and cradle will roll until the cradle is all the way in and further movement is then accomplished by sliding the drawer along its glides 45. The drawer is prevented from tipping by means of the retainers 30 wherein the fingers 30a engage over the bottom flanges 43c and 44c of the cradle. From a consideration of FIG. 21, it will be observed that the flanges 43b and 44b are wider at the rear as at 43c and 44c and that notches 43d and 44d are provided. In inserting a drawer into a cradle, the rear end of the drawer is inserted and the drawer is then pushed back so that the fingers 30a engage under the channels 43c and 44c. In the event that accidentally the fingers 30a happen to be on top of the channels 43c and 44c, when the drawer is pushed in to the point where the fingers 30a reach the slots 43d and 44d, the fingers will drop through the slots and the drawer will attain its proper position.

As pointed out heretofore, the drawer false front 25 is provided with the upper and lower flanges 26 and 27 and the lateral flanges 28 and 29 as shown in FIG. 24. For each drawer there is provided a finish front. The finish front will have the rearwardly sloping flanges on three sides adapted to mate with the flanges on the false front and on the fourth side there will be provided an elongated hook element 50. In FIG. 24, there is shown the upper rearwardly sloping flange 51 and one of the laterally rearwardly sloping flanges 52. As shown in the broken lines in FIG. 24 the false front is started from the top with the side flanges 52 and 28 and the corresponding side flanges on the other side forming a dovetail. The finish front is slid downwardly until the top flange 51 abuts the

flange 26 with the hook element 50 snapping over the bottom flange 27 of the false front. This is clearly shown in FIG. 24. A drawer pull 55 may then be attached by means of a screw 56 as also shown in FIG. 24. FIG. 26 shows a similar arrangement in a file drawer rather than the box drawer of FIG. 24.

In some styles of desks it is desirable to eliminate drawer pulls in the conventional sense. In this case a lateral overhang is provided as indicated at 57 in FIG. 25. In FIG. 25 the pedestal shown would be the right-hand pedestal and a drawer is pulled out by pulling with the fingers on the overhang 57. The overhang 57 is exposed in the knee-hole area of the desk. It will now be understood that if it is desired to interchange a drawer from a right-hand to a left-hand pedestal, a finish front 58 as shown in FIG. 25 must be turned 180° so that the overhang 57 will appear at the right-hand side of the drawer. In this situation, therefore, the finish front 58 is slid into position horizontally rather than vertically and again it is slid into position until the hook element 57a engages over the false front flange 28 or 29 as the case may be. To change the drawer from the right-hand side to the left-hand side, it is only necessary to unhook the hook member 57a and slide the finish front 58 off toward the left, turn it 180° and slide it on again from the right until the hook member 57a engages over the flange 29.

From the foregoing description it will be clear that the drawers of a desk according to the present invention are fully interchangeable from one position to another in the same pedestal or from one pedestal to the other pedestal, or from one desk to another desk of the same construction. It will be clear that numerous modifications may be made without departing from the spirit of the invention and no limitation is therefore intended which is not set forth in the claims which follow.

The embodiments of the invention in which an exclusive property or privilege is claimed are defined as follows:

1. In a pedestal type desk, at least one standard pedestal weldment, fastening elements along all vertical corners of said weldment adapted to receive a variety of corner trim elements and combined trim and leg elements, and a plurality of matching corner trim elements and combined trim and leg elements, each of said elements having cooperating fastening elements, whereby the location of the legs and the number of the legs and the style of the desk may readily be changed without the use of special tools.

2. The structure of claim 1, wherein the fastening elements on said weldment are keyhole slots having the restricted portions thereof upwardly directed, and the fastening elements on said trim elements and combined trim and leg elements are headed studs having heads of a size which will pass through the large portion but not the restricted portion of said keyhole slots.

3. The structure of claim 1, wherein standard drawer case elements are suitably secured on opposed sides of the interior of said pedestal weldment, said case elements being generally channel shaped with the arms of said channels inwardly directed, each of said case elements having a stud for the mounting of a drawer supporting roller, and a slot for the mounting of a drawer supporting nylon glide, whereby several modes of drawer suspension may be provided in said standard pedestal weldment with the standard case elements.

4. The structure of claim 3 in combination with nylon glides secured to said case elements by snap engagement with said slots.

5. The structure of claim 3 in combination with anti-friction rollers rotatably secured on said studs.

6. In a pedestal type desk having a standard pedestal weldment, a standard drawer, a drawer suspension comprising a pair of standard case elements secured in mutually opposed position on the inside of said pedestal, each of said case elements being generally channel shaped with the arms of said channels inwardly directed, each of

said case elements having, adjacent the front of said pedestal, a stud for the mounting of a drawer supporting roller, and a slot for the mounting of a drawer supporting nylon glide, roller means associated with each side of said drawer at its inner end for engaging said case elements, whereby selectively several modes of suspension may be provided in said standard pedestal for said standard drawer.

7. The structure of claim 6, wherein a nylon glide is secured to each of said case elements by snap engagement with said slots, and said drawer is provided with a roller on each side adjacent its rear end, said rollers engaging in said case elements; and said nylon glides supporting the bottom of said drawer.

8. The structure of claim 6, wherein a roller is mounted on each of the studs of said case elements, and said drawer is provided with a runner on each side adapted to ride on said rollers, and said runner is provided with a roller on each side adjacent its rear end, said last mentioned rollers engaging in said case elements.

9. The structure of claim 6 in combination with a cradle, a roller mounted on each of the studs of said case elements, said cradle being provided with a runner on each side adapted to ride on said rollers, and said cradle being provided with a roller on each side adjacent its rear end, said last mentioned rollers engaging in said case elements, said cradle having nylon glides for the drawer bottom and sides, and said drawer being shorter than said cradle, resting in said cradle and arranged for limited sliding movement fore and aft with respect to said cradle, whereby when said drawer is pulled out, the drawer and cradle move as a unit until the limit of withdrawal of

said cradle, whereupon said drawer may be pulled out in sliding movement in said cradle until the rear of said drawer is substantially flush with the front of said pedestal.

5 10. The structure of claim 6, wherein said drawer is provided with a false front having upper, lower and lateral, forwardly sloping flanges, said drawer being provided with a finish front member having along three sides a mating flange engageable with respective sloping flanges of said false front, and along its fourth side having a hook element, whereby said finish front may be applied to said false front by engaging the opposed flanges of said finish front adjacent said hook element with opposed flanges of said false front and sliding it into a position in which said hook element snaps over the far flange on the said false front.
